DESIGN FOR A BLOUSE

Henriette de Bernard, St. Louis, Mo.

Application December 8, 1937, Serial No. 73,448

Term of patent 3½ years

To all whom it may concern:

Be it known that I, Henriette de Bernard, a citizen of the United States of America, residing in the city of St. Louis and State of Missouri, have invented a new, original, and ornamental Design for a Blouse, of which the following is a specification, reference being had to the accompanying drawing, forming part thereof, wherein,

My design is characterized by the specific link button arrangement in combination with the specific blouse as shown.

I claim:

The ornamental design for a blouse, substantially as shown, and described.

HENRIETTE DE BERNARD.
